CLAIM

The ornamental design for a medical dressing support frame with tab, as shown and described.

DESCRIPTION

FIG. 1 is a top, perspective view of an illustrative embodiment of a medical dressing support frame with tab according to this specification;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is rear view thereof.

The broken lines in the drawings are included for the purpose of illustrating environmental structure and form no part of the claim.
